Atty's.

UNITED STATES PATENT OFFICE.

WILLIAM F. GRAUL, OF NORTHAMPTON, MASSACHUSETTS, ASSIGNOR TO FANNIE B. LOOK AND WILLIAM CORDES, OF NORTHAMPTON, MASSACHUSETTS, ELDON MACLEOD, OF WESTWOOD, MASSACHUSETTS, AND GEORGE H. BURR, OF NEW YORK, N. Y., TRUSTEES, DOING BUSINESS AS FLORENCE MANUFACTURING COMPANY.

DESIGN FOR A TOOTH-BRUSH HANDLE.

52,390.

Specification for Design. Patented Sept. 10, 1918.

Application filed March 25, 1918. Serial No. 224,635. Term of patent 14 years.

To all whom it may concern:

Be it known that I, WILLIAM F. GRAUL, a citizen of the United States, residing at Northampton, county of Hampshire, State of Massachusetts, have invented a certain new, original, and ornamental Design for Tooth-Brush Handles, of which the following is a specification, reference being had therein to the accompanying drawings.

In the drawings Figure 1 is a side view and Fig. 2 is a plan view of a tooth brush handle, showing my new design.

I claim

The ornamental design for a tooth brush handle, as shown.

WILLIAM F. GRAUL.
